UNITED STATES PATENT OFFICE.

CARMON F. HEPLER, OF PHILLIPSTON, PENNSYLVANIA.

RAIL-TIE.

1,205,992.

Specification of Letters Patent. Patented Nov. 28, 1916.

Application filed December 1, 1915. Serial No. 64,567.

To all whom it may concern:

Be it known that I, CARMON F. HEPLER, a citizen of the United States, residing at Phillipston, in the county of Clarion and State of Pennsylvania, have invented certain new and useful Improvements in Rail-Ties, of which the following is a specification.

My present invention has relation to certain new and useful improvements in rail ties and more specifically comprehends novel means to effectually clamp the rail thereon; and as its primary object, it contemplates the provision of a device of this nature that includes means to yieldingly hold the rail in position, retain the same rigid against a downward pressure and, at the same time, permit slight rebound and lateral give of the rail during and after the passing of rolling stock thereover.

Another object of my invention is to provide means to effectually adjust the tension of the clamping means so as to provide for the proper securing of the rail, at all times, and especially after the base flange thereof has become worn to some extent.

A further object of the invention is to provide an improved form of tie body designed to accommodate the aforesaid clamping means and tensioning device and at the same time efficiently support the respective rail and eliminate any downward movement thereof.

A still further object of my invention is to provide a device of the type in question that is extremely simple in construction, strong and durable, and highly practical from both the standpoint of the manufacturer and the standpoint of the user; and which, it is believed, may be manufactured at a comparatively low cost.

Various other objects and advantages will become apparent during the continuance of the following description.

These objects are accomplished by such means as are shown in their preferred form in the accompanying drawings, described in the following specification and then more specifically pointed out in the appended claims.

In the accompanying drawings wherein like characters designate like parts throughout the several views, Figure 1 is a view in side elevation showing the same as in its preferred embodiment and properly associated with an ordinary rail; Fig. 2 is a view in

longitudinal section illustrating more clearly the method of clamping the rails to the tie; Fig. 3 is a view in horizontal section illustrating the disposition of the clamping member; Fig. 4 is a view in detail showing the means for retaining the fastening member in certain adjusted positions; and Fig. 5 is a view in detail of the means to adjust the tensioning member.

In reducing my invention to practice, I first provide a tie body 10 that is preferably constructed to be substantially U-shaped when viewed in section and formed of metal or a like material. Intermediate its ends, the body 10 is provided with oppositely projecting chair portions 11 and 12 respectively, upon which the rail 13 is adapted to rest, such as shown in Fig. 1. Although not essential to the efficient operation of the device, the chair portions 11 and 12 above referred to may be made hollow in their longitudinal extent such as shown in Fig. 1 so as to decrease the cost of manufacture. Adjacent its respective ends, the body 10 is provided with detachable covering plates 14 and 15 respectively, whose openings 16 receive base studs 17 of the body member in the manner indicated in Fig. 4. The inner ends of the covering plates 14 and 15 normally bear against suitable transverse stopping members 18 and 19 between which the rail 13 normally seats. It is contemplated that the stopping members 18 and 19 be spaced apart a distance materially greater than the width of the base flange of the rail so as to not only accommodate suitable clamping members such as will be subsequently pointed out, but to permit a slight lateral give of the rail and the clamping members as before stated. This function, however, will be hereinafter described at length.

In order to secure the covering plates 14 and 15 in place prior to the operation of the positive locking means, I may provide the body member 10 with suitable retaining members 20, preferably in the form of springs, having one end fixed to the body as at 21 and their other end bent as at 22 to engage with the respective plates. This construction enables the operator to properly position the cover plates on the body member and retain the same against dislodgment prior to the manipulation of the positive locking means. Furthermore, it will be

seen that by properly applying the retaining members 20 the plates may be quickly and easily removed from such locked position.

With a view of providing suitable fastening means for the rails I employ substantially U-shaped members 23 and 24 respectively whose bridge or intermediate portion 25 is received in suitable notches 26 of a connecting bar 27. At their upper ends the arms of the respective clamping members are bent to form ears 28 which may be brought into secure binding engagement with the base flange of the rail in the manner shown in Fig. 2. Upon reference to Fig. 15, it will be noted that the connecting bar 27 has its upper face beveled as at 29 from a central point toward its ends. The function of this beveled portion will be subsequently pointed out. The clamping members just referred to, as well as the connecting bar 27 may also be formed of metal so as to be capable of withstanding the terrific pressure subjected thereon at certain times and to insure efficient clamping of the rails. 25

Adjacent opposite ends, the side members 30 of the tie are provided with vertically disposed ribs 31 and 32 respectively, whose inner face is provided with a series of ratchet teeth 33 such as clearly shown in Fig. 4. 30

Opposite the ribs 31 and 32 respectively, the side members 30 are provided with spaced guiding members 34 and 35. Although not essential to the invention, it is pointed out that the ribs 31 and 32 as well as the respective guiding members 34 and 35 may be cast integral with the body of the tie so as to decrease cost of manufacture.

A tensioning member 36 is arranged to extend between the respective arms of the clamping members 24 and engage with the connecting bar 27 in the manner clearly shown in Fig. 2. The end portions of this tensioning member also project between the ribs 31 and 32 and the respective guiding members whereby they will be securely retained, in the manner that will subsequently appear. In order that it may be effectually engaged with the ratchet teeth 33 of the ribs, the tensioning member 36 is cut away as at 38 adjacent its ends, preferably upon opposite sides. Consequently by forcing a wedge key or other member such as indicated by the numeral 39 between the guiding members such as shown in Fig. 4, the respective end of the tensioning member 36 will be properly engaged with the ratchet teeth 33 of the ribs and thus held in a secure position. It is contemplated that one end of the tensioning member be fastened in this manner, that is, through the manual operation thereof, while provision is made to effectually adjust the other end thereof so as to complete the desired pressure on the connecting bar 27. To this end, I provide 65

65 the side members 30 of the tie body with

spaced blocks 40 (see Fig. 4) whose under faces form suitable stopping shoulders to be engaged by lugs 41 on the clamping yoke 42. The respective end of the tensioning member is now provided with a suitably threaded shank 43 that is adjustably mounted through the yoke 42 and which may be properly manipulated by a handle portion 44. By rotating the shank 43 in a certain direction, the respective end of the tensioning member will be depressed to the desired extent while the block 40 effectually precludes upward movement of the clamping yoke. Therefore, after the respective end of the tensioning member has been depressed to the desired extent, a wedging key such as shown at 39 may be engaged with the respective guiding members so as to force the tensioning member into seating engagement with a certain one of the ratchet teeth 33 of the ribs. Consequently, it will be noted that the member 36 will be securely retained in a tensioned position and likewise retain the respective clamping members 24 in binding engagement with the rail.

Upon reference to Fig. 2, it will be noted that when the member 36 is drawn into a tensioned position a spring action will be generated between the under enlarged face of the member 36 and the beveled face 29 of the connecting bar. This not only serves to permit slight vertical movement of the rail after the passage of rolling stock thereover but also permits a slight lateral give thereof, which, is believed to be also highly desirable.

Any number of the ratchet teeth 33 may be provided throughout the longitudinal extent of the ribs 31 and 32 which will permit the adjustment of the tensioning member to any desired extent. It is pointed out, therefore, that should the tensioning members become weakened at any time they may be bent to a greater degree and thus not in any way lessen the efficiency of the device.

While in the present embodiment, I have shown my invention in connection with only one rail, it is to be fully understood that the body portion 10 may be constructed of any length to support both of the rails. This, however, is immaterial and further detail description is deemed unnecessary.

In reducing my invention to practice I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention as defined in the appended claims.

Having thus fully described my invention,

what I claim as new and desire to secure by Letters Patent is:—

1. In a device of the character described, a rail tie, rail clamping means associated therewith, a tensioning member coöperating with said clamping means, means to adjust said tensioning member to vary the tension exerted on said clamping means, and means to retain said tensioning member in certain adjusted positions, as and for the purpose specified.

2. In a rail tie, means to support the rail, rail clamping means movably associated with said supporting means, a tensioning member coöperating with said clamping means, means to lock one end of said tensioning member with respect to said supporting means, means to adjust the other end of said tensioning member whereby the tension on said clamping means may be varied, and means to lock the last mentioned end of said tensioning member in certain adjusted positions, as and for the purpose specified.

3. In a device of the character described, a rail tie including rail supporting means, rail clamping means associated therewith, a tensioning member coöperating with said rail clamping means, means to lock one end of said tensioning member with respect to said supporting means, means to adjust the other end of said member whereby the tension on said clamping means may be varied, means to shift the last mentioned end of said tensioning member laterally, and means to lock the last mentioned end of said tensioning member in certain adjusted positions, as and for the purpose specified.

4. In a device of the character described, rail supporting means, clamping means associated therewith, a tensioning member coöperating with said clamping means, means to lock one end of said tensioning member with respect to said supporting means, means to adjust the other end of said tensioning member whereby the tension on said clamping means may be varied, a wedge to shift the last mentioned end of said tensioning member laterally, and means carried by said supporting means to lock said last mentioned end of said tensioning member in certain adjusted positions, as and for the purpose specified..

5. In a device of the character described, rail supporting means, rail clamping means 55 movably associated therewith, a tensioning member coöperating with said clamping means, means to shift one end of said tensioning member laterally, means adjacent that end of said member to lock the same 60 stationary with respect to said supporting means, means to adjust the other end of said tensioning member whereby the tension on said clamping means may be varied, means to shift the last mentioned end of 65 said tensioning member, and means carried by said supporting means to lock said last mentioned end of said tensioning member in certain adjusted position, as and for the purpose specified. 70

6. In a device of the character described, a rail tie, rail clamping means movably associated therewith, a tensioning member coöperating with said clamping means and disposed longitudinally within said rail tie, 75 means to adjust the ends of said tensioning member vertically to vary the tension on said clamping means, and means to retain the ends of said tensioning member at certain adjusted positions. 80

7. In a device of the character described, a rail tie hollow throughout a portion of its length, rail clamping means movably associated therewith, a tensioning member coöperating with said clamping means, said tensioning member being disposed longitudinally within said tie, ratchet bars disposed on opposite sides of the hollow portion of said tie and adjacent opposite ends thereof, guide means positioned opposite said ratchet 90 bars, the end portions of said tensioning member being disposed between said ratchet bars and said guide means, means to adjust the end portions of said tensioning member to vary the tension on said clamping means, and wedge members operable in said guide means to shift said tensioning member into engagement with said ratchet bars to retain the same in certain adjusted positions, substantially as described. 95 100

In testimony whereof I affix my signature in presence of two witnesses.
